FIG. 3

FIG. 4

FIG. 5

UNITED STATES PATENT AND TRADEMARK OFFICE
Certificate

Patent No. D 460,683 S

Patented: July 23, 2002

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Kuo-Chi Yen, Taichung, Taiwan.

Signed and Sealed this Fourteenth Day of October 2003.

ALAN P. DOUGLAS
Supervisory Patent Examiner
Art Unit 2911
